UNITED STATES PATENT OFFICE.

HOWARD M. BARBER, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

FOLDING-MACHINE.

1,200,573.

Specification of Letters Patent. Patented Oct. 10, 1916.

Application filed February 12, 1913. Serial No. 748,088.

To all whom it may concern:

Be it known that I, HOWARD M. BARBER, a citizen of the United States, and resident of Stonington, in the county of New London 5 and State of Connecticut, have invented a new and useful Improvement in Folding-Machines, of which the following is a specification.

The object of my invention is to provide 10 novel means whereby the entire product of a printing press may be folded off and delivered together or whereby the product may be divided and folded off and delivered to two different points so that the product 15 may be folded into signatures having a different number of pages without in any way affecting or changing the speed of the press.

My invention comprises three rotary carriers, one of the carriers being arranged to 20 coat with one only of the other carriers when the entire product is folded off thereto or to coat with both carriers alternately when part of the product is delivered to one carrier and the balance to the other carrier; 25 both folding off operations in the last instance being from the same side of the web.

My invention comprises novel means for controlling the floating of a tucking blade whereby it is caused to coact with the floating 30 folding jaws on one rotary carrier or to coat with the floating folding jaws carried by two independent rotary carriers.

My invention more particularly comprises 35 means for controlling the operation of the cam which floats the tucking blade whereby the tucking blade is caused to coact with either of the floating folding jaws for the purposes above set forth.

A practical embodiment of my invention 40 is represented in the accompanying drawings, in which—

Figure 1 represents in side elevation that part of a folding machine which embodies my invention, Fig. 2 is a diagrammatic vertical section taken from front to rear through the machine, Fig. 3 is a detail plan view at one side of the machine, the web feeding devices and rotary cutters being removed, Fig. 4 is a similar view at the other 45 side of the machine, Fig. 5 is a section taken in the plane of the line A—A of Fig. 3, Fig. 6 is a section taken in the plane of the line B—B of Fig. 4, and Fig. 7 is a detail view of the alternate cam for controlling the

opening of the grippers on the folding cylinder. 55

The web, not shown, is fed from the printing press to the folding machine by the endless tapes and rollers 1, 2, 3, 4, 5. The web is severed transversely into sheets by the 60 pair of coacting rotary cutters 6, 7, and is directed downwardly to the grippers 8 of the collecting and male folding cylinder 9 through guides 10, 11.

The floating tucking blade 12 on the male 65 folding cylinder 9 is arranged to coact with the floating folding jaw 13 of the female folding cylinder 14 for folding off the entire product thereto or to coact alternately with the said floating folding jaw 13 of the cylinder 14 and the floating folding jaw 15 of the female folding cylinder 16 for folding off part of the product to the cylinder 14 and part of the product to the cylinder 16. 70

The folded product may be conveyed from 75 the floating folded jaw 13 to any desired point by means of endless tape carriers 17, 18, 19, and their pulleys 20, 21, 22, 23, 24, 25, 26. The folded product may be conveyed from the floating folding jaw 15 to 80 any desired point by means of the endless tape carriers 27, 28, 29, and their pulleys 30, 31, 32, 33, 34, 35, 36, 37.

In the arrangement of the parts as herein shown, the cylinder 9 either folds off a collected group of two sheets to the cylinder 14 every second revolution of the cylinder 9 or folds off one sheet to the cylinder 14 85 every second revolution of the cylinder 9 and one sheet to the cylinder 16 every second revolution of the said cylinder 9, the folding off operations alternating. If for instance, each sheet were eight pages, either a sixteen page product would be folded off to the cylinder 14 or an eight page product 90 would be folded off to each of the cylinders 14 and 16, without affecting or changing the speed of the press. 95

The means which I employ to carry out the above results, are constructed, arranged 100 and operated as follows: The cams for floating the tucking blade 12 and the folding jaws 13 and 15 are of well known and approved construction, the cam for floating the tucking blade being denoted by 38, the 105 cam for floating the folding jaw 13 by 39 and the cam for floating the folding jaw 15 by 40. The cam for opening the folding

jaw 13 at the time of the fold is denoted by 41 and the cam for opening the folding jaw 15 at the time of fold is denoted by 42. The cam for opening the folding jaw 13 at the 5 time of delivery is denoted by 43 and the cam for opening the folding jaw 15 at the time of delivery is denoted by 44. The cams 43 and 44 are both fixed to one of the side frames of the machine as clearly shown in 10 Fig. 3.

The geared connection between the several parts is as follows: The gear 45 is driven from the press by means, not shown herein, at the proper speed. This gear 45 15 is fast on the shaft 46 of the collecting and folding cylinder 9. This gear meshes at all times with a gear 47 fast on the shaft 48 of the female folding cylinder 14. A gear 49 has a sliding interlocked engagement on the 20 shaft 50 of the female folding cylinder 16 so that the said gear 49 may be shifted into and out of engagement with the gear 45 according to whether the product is to be divided and to be delivered at two separate 25 points or is to be combined and delivered at a single point. Interchangeable cams 51 and 52 are provided for opening the grippers 8 on the collecting and folding cylinder 9. One of these cams, in the present 30 instance the cam 51, is mounted on a rotary support concentric with the axis of the folding cylinder 9 and is driven at one-half the speed of the said folding cylinder 9, as follows: A gear 53 is fast on the shaft 46, 35 which gear meshes with a gear 54 on a stud shaft 55 and a gear 56 fixed to rotate with the gear 54 meshes with the gear 57 which forms the rotary support for the cam 51 or the cam 52, as the case may be. It will be 40 seen, therefore, that the gear 57 is loosely mounted on the shaft 46 and the relationship of the gears is such that the gear 57 travels at one-half the speed of the cylinder 9. The rotary cutters 6 and 7 and the feeding 45 and delivery carriers are driven at the desired speeds in the usual manner. The cam for controlling the floating of the tucking blade 12 is reciprocated to float the blade in parallelism with both the jaw 13 and 50 the jaw 15 when the product is divided. A gear 58 fast on the shaft 50 of the female folding cylinder 16 is provided with a box cam 59 which controls the movement of a reciprocating rack 60, which rack meshes 55 with a gear 61 fast on the stud shaft 62. A gear 63 also fast on the shaft 62 meshes with a gear 64 loosely mounted on the shaft 46 but fast to the cam 38 which controls the floating of the tucking blade 12. The mechanism 60 for reciprocating the cam 38 is only operative when the gear 49 is brought into mesh with the driving gear 45. When the gear 49 is moved out of mesh with the gear 45, the cam 38 is held stationary after having 65 been adjusted to the proper point for

floating the tucking blade into parallelism with the gripper 13 of the female folding cylinder 14 by a clutch 65 adapted to be moved into engagement with the teeth of the gear 58. Suitable fastening means 66 70 are provided for locking the clutch 65 in its operative and inoperative positions. It is to be understood that when the gear 49 is in mesh with the gear 45, the clutch 65 is out of engagement with the gear 58. It will 75 furthermore be seen that when the gear 58 is locked against movement, the cam 38 is also locked against movement and the female cylinder 16 and its delivery mechanism is also locked against movement. 80

I will proceed to describe the operation of my invention with the parts in the positions which they assume for folding off the entire product in one direction. The gear 49 is disengaged from the gear 45 and the gear 58 is locked with the cam 38 in position to float the tucking blade 12 in parallelism with the folding jaw 13. The first sheet severed from the web by the rotary cutters 6, 7, is taken by the grippers 8 of 90 the cylinder 9 and carried around thereby. This sheet is then associated with the next succeeding sheet severed from the web by the rotary cutters and at the proper time the collected group of two sheets is folded off 95 by the coaction of the tucking blade 12 and grippers 13 to the cylinder 14 and delivered from the cylinder to any suitable point. In this instance, the cam 51 is attached to the rotary support 53 which travels at one-half 100 the speed of the cylinder 9. When it is desired to fold off half the product in one direction and half the product in another direction, the gear 58 is released and the gear 49 is brought into driving engagement with 105 the gear 45, and the cam 52 is substituted for the cam 51 on the rotary support 53. The parts are then so arranged that the grippers 8 on the cylinder 9 will take the first sheet severed from the web by the cutters 6, 7, and release the sheet at the proper time to permit the same to be folded off to the cylinder 16 by the coaction of the tucking blade 12 with the folding jaw 15. The 110 next succeeding sheet will pass between the cylinders 9 and 14 by gravity with its leading edge free and at the proper time the sheet will be folded off to the cylinder 14 by the coaction of the tucking blade 12 with the folding jaw 13. To bring the tucking blade 12 into parallelism with both the folding jaw 13 and the folding jaw 15, the cam 38 is reciprocated under the control of the cam 59 on the gear 58. 115

From the above description, it will be seen 125 that without in any way affecting or changing the speed of the press, the product of the press may be collected, folded and delivered in one direction or may be divided, folded and delivered in different directions, 130

the folds being from the same side of the web sheets where the product is divided.

What I claim is:—

1. In a folding machine, a rotary sheet 5 collecting carrier having a tucking blade and means for causing it to fold off a sheet at each of different points or a collected group of sheets at one of said points only.

2. In a folding machine, a rotary sheet 10 collecting carrier having a tucking blade and means for causing it to fold off a sheet at each of two points or a collected group of sheets at one of said points only.

3. In a folding machine, a rotary sheet 15 collecting carrier having a tucking blade and means for causing it to fold off one sheet at each of two points or a collected group of two sheets at one of said points only.

4. In a folding machine, a rotary sheet 20 collecting carrier having a tucking blade and means for causing it to fold off a collected product at one point or to fold off part of the product at each of different points.

5. In a folding machine, a rotary sheet 25 collecting carrier having a tucking blade and means for causing it to fold off a collected product at one point or to fold off part of the product at each of two points.

6. A folding mechanism comprising a 30 plurality of fixedly mounted rotary carriers, another rotary carrier and means for causing it to coact with one or all of said plurality of rotary carriers to fold off sheets thereto.

7. A folding mechanism comprising two 35 fixedly mounted rotary carriers, a third rotary carrier and means for causing it to coact with one or both of said two rotary carriers to fold off sheets thereto.

8. A folding mechanism comprising a 40 plurality of fixedly mounted rotary carriers, another rotary carrier and means for causing it to collect and fold off all the sheets to one of the first-named rotary carriers or to fold off sheets to each of said first-named carriers.

9. A folding mechanism comprising two 45 fixedly mounted rotary carriers, a third rotary carrier and means for causing it to collect and fold off all the sheets to one of the first-named rotary carriers or to fold off sheets to each of said first-named carriers.

10. A folding mechanism comprising a 50 plurality of fixedly mounted rotary carriers having folding jaws, another rotary carrier having a tucking blade and means for causing it to coact with the folding jaws of one or all of said first-named carriers.

11. A folding mechanism comprising two 55 fixedly mounted rotary carriers having folding jaws, a third rotary carrier having a tucking blade and means for causing it to coact with the folding jaws of one or both of said first-named carriers.

12. A folding mechanism comprising a 60

plurality of fixedly mounted rotary carriers having floating folding jaws, another rotary carrier having a floating tucking blade and means for causing it to coact with the floating folding jaws of one or all of said first- 70 named carriers.

13. A folding mechanism comprising two fixedly mounted rotary carriers having floating folding jaws, a third rotary carrier having a floating tucking blade, means for causing it to coact with the floating folding jaws 75 of one or both of said first-named carriers.

14. A folding mechanism comprising a plurality of fixedly mounted rotary carriers having folding jaws, another rotary carrier 80 having a tucking blade and a single means for operating the blade to cause it to coact with the folding jaws of one or all of said first-named carriers.

15. A folding mechanism comprising two 85 fixedly mounted rotary carriers having folding jaws, a third rotary carrier having a tucking blade and a single means for operating the blade to cause it to coact with the folding jaws of one or both of said first- 90 named carriers.

16. A folding mechanism comprising a plurality of fixedly mounted rotary carriers having floating folding jaws, another rotary 95 carrier having a floating tucking blade and a single means for floating the blade to cause it to coact with the floating folding jaws of one or all of said first-named carriers.

17. A folding mechanism comprising two fixedly mounted rotary carriers having floating folding jaws, a third rotary carrier having a floating tucking blade and a single means for floating the blade to cause it to coact with the floating folding jaws of one 100 or both of said first-named carriers. 105

18. A folding machine comprising two rotary carriers having folding jaws and another rotary carrier having a tucking blade, cams for floating the folding jaws and tucking blade and means for moving the tucking blade controlling cam to cause the tucking 110 blade to be brought into coaction with the folding jaws of each of said first-named rotary carriers.

19. A folding machine comprising two 115 rotary carriers having folding jaws and another rotary carrier having a tucking blade, cams for floating the folding jaws and tucking blade, means for moving the tucking blade controlling cam to cause the tucking 120 blade to be brought into coaction with the folding jaws of each of said first-named rotary carriers, and means for disconnecting one of said first-named carriers.

20. A folding machine comprising two 125 rotary carriers having folding jaws and another rotary carrier having a tucking blade, cams for floating the folding jaws and tucking blade and means for moving the tucking blade controlling cam to cause the tucking 130

blade to be brought into coaction with the folding jaws of each of said first-named rotary carriers, means for disconnecting one of said first-named carriers and means for holding the tucking blade controlling cam stationary when so desired.

In testimony, that I claim the foregoing

as my invention, I have signed my name in presence of two witnesses, this tenth day of February A. D. 1913.

HOWARD M. BARBER.
